UNITED STATES PATENT OFFICE.

RALPH E. BLETCHER AND ERNEST H. BUCKNELL, OF LOS ANGELES, CALIFORNIA.

DESIGN FOR AN ESCUTCHEON.

Application filed June 6, 1928. Serial No. 27,020. Term of patent 7 years.

To all whom it may concern:

Be it known that we, RALPH E. BLETCHER and ERNEST H. BUCKNELL, citizens of the United States of America, and residents of Los Angeles, in the county of Los Angeles and State of California, have invented a new, original, and ornamental Design for Escutcheons, of which the following is a specification, reference being had to the accompanying drawing, forming part thereof,

In the drawing,
Figure 1 is a plan view of the escutcheon;
Figure 2 is a front view thereof;
Figure 3 is an end view of same; and
Figure 4 is a bottom plan view thereof.
We claim:
The ornamental design for an escutcheon, as shown.

ERNEST H. BUCKNELL.
RALPH E. BLETCHER.
